(57) **CLAIM**

The ornamental design for an optical fiber fusion splicer, as shown and described.

DESCRIPTION

FIG. 1 is a front view of an optical fiber fusion splicer of the present invention.

FIG. 2 is a rear view of the optical fiber fusion splicer of FIG. 1.

FIG. 3 is a top plan view of the optical fiber fusion splicer of FIG. 1.

FIG. 4 is a bottom view of the optical fiber fusion splicer of FIG. 1.

FIG. 5 is a right side view of the optical fiber fusion splicer of FIG. 1.

FIG. 6 is a left side view of the optical fiber fusion splicer of FIG. 1.

FIG. 7 is a front perspective of the optical fiber fusion splicer of FIG. 1; and,

FIG. 8 is a rear perspective view of the optical fiber fusion splicer of FIG. 1.

The features shown in broken lines depict environmental subject matter only and form no part of the claimed design.
